UNITED STATES PATENT OFFICE.

GLENN O. WILLHIDE, OF BALTIMORE, MARYLAND.

FUEL FEEDER.

Application filed June 29, 1927. Serial No. 202,389.

My present invention has reference to an automatic stoker which is primarily designed for feeding the fire of a locomotive but may, of course, be successfully employed for feeding fires of other furnaces, and my object is to simplify and improve the existing art by producing a steam jet of a novel construction which employs fewer parts than those of the usual type, which may be attached to the furnace in an easier and quicker manner than is usual and which will spread the fuel in an even manner over the entire grate surface.

A still further object is the provision of a jet for mechanical or automatical stokers that includes a head having steam passages therethrough and nozzles at the outlet end of the head, and which also includes a steam chest which is directly connected to the head and has ports alining with the passages in the head, and each of the said ports is individually controlled by a needle valve so that the passage of steam through any one of the ports may be regulated to insure an even distribution of the steam and likewise an even distribution of the fuel in the fire box, a single hand operated valve controlling the admission of steam to the chest.

The invention will be fully and comprehensively understood from a consideration of the following detailed description when read in connection with the accompanying drawings which form part of the application, with the understanding, however, that the improvement is capable of extended application and is not confined to the exact showing of the drawings nor to the precise construction described and, therefore, such changes and modifications may be made therefrom as do not affect the spirit of the invention nor exceed the scope thereof as expressed in the appended claim.

In the drawings:

Figure 1 is a detail sectional view through a sufficient portion of the fire box of a locomotive to illustrate the application of my improvement thereon.

Figure 2 is a top plan view of the improvement with parts broken away and parts in section.

Figure 3 is an end view thereof.

Figure 4 is a sectional view on the line 4—4 of figure 2.

Figure 5 is a detail enlarged sectional view on the line 5—5 of Figure 2.

In the ordinary steam jet construction for mechanical stokers the steam inlet chamber or chest is arranged against the outer wall of the furnace below the door and has connected thereto a plurality of tubes which extend downwardly therefrom and have branches that pass through the said furnace wall and which branches are provided with coupled extensions that are connected directly to the head of the jet. The tubes are, of course, individually controlled by valves. The construction is complicated, requires a comparatively greater amount of time and labor in the installation thereof, does not permit of repairs or replacement of parts in an easy manner and comprises a comparatively large number of elements so as a whole the device is complicated, expensive in manufacture and likewise expensive in installation.

With the improvement the steam chamber or chest is directly connected to the head of the jet and, therefore, the parts are in longitudinal alinement. This permits of the improvement being arranged in the doorway of the furnace, and only necessitating a partial cutting away of the lower portion of the door.

The steam receiving member of the improvement is in the nature of a metal block, and is also in the nature of a steam chest and will be thus hereinafter referred to. The chest is indicated by the numeral 1 and the steam compartment therein by the numeral 2. The outer straight wall of the steam chest 1 is bored to provide any desired number of longitudinally arranged equidistantly spaced threaded openings, and in each of these openings, there is screwed a nipple 3. The inner wall of the steam chest is centrally formed with a substantially rectangular depression or pocket 4, whose walls are preferably arranged directly opposite the walls of the chamber 2. From the inner wall of the chamber 2 the block con-

stituting the steam chest is bored to provide threaded openings that are arranged each directly opposite the openings in which the nipples 3 are screwed. These openings are 5 smaller than the openings for the nipples and screwed in these openings there are other nipples 5. The nipples 5 have headed ends that are received in the chamber 2, and the bore of the device, at the heads thereof are 10 preferably flared and provide seats for the conical ends 7 of needle valves 8. The valves 8 have threaded portions 9 that are screwed through the nipples 3, and the outer ends of the nipples have screwed thereon 15 cap nuts 10 which are in the nature of packing boxes and through which the valves 8 pass. The outer ends of the valves are squared, as at 11, for the reception of a suitable wrench or handle whereby the separate 20 valves may be regulated with respect to their seats.

The inlet pipe for the chamber of the steam chest is vertically disposed and is indicated by the numeral 12. The passage 25 through this pipe is controlled by a hand valve 13, and the pipe is, of course, directed to the steam supply.

The distributor or jet head is also in the nature of a metal block, and as a whole the 30 same is indicated by the numeral 14. The outer end of the head is rounded, and the inner end thereof is formed with a widened and thickened portion 15 that is centrally formed with a substantially rectangular lug 35 16 to be received in the pocket or depression 4 in the inner face of the valve chest. Passing through openings in the end 15 of the head 14, and through similar openings in the steam chest there are bolt members 17 40 engaged by the usual nuts 18. The bolt members compress between the confronting surfaces of the steam chest and the head 14 a gasket 19. This insures a fluid tight joint between the elements constituting the improvement.

The nozzle head 14 is provided with longitudinally arranged preferably equidistantly spaced passages 20 which communicate between the straight and rounded ends of the 50 head. These passages 20 also communicate with openings 19' in the gasket, the said openings being disposed opposite the valve seats or nipples 5. The rounded outer end of the head has screwed therein nozzles 21 55 which communicate with the respective passages 20.

As disclosed by Figure 1 of the drawings, the nozzle end of the jet head 14 is arranged directly over the vertical conveyor housing 60 22 of the stoker, and the mouth or outlet of the housing is surrounded by a protecting grate 23 of the usual construction.

With my improvement the fireman, by merely opening the door 24 of the furnace 65 25, can observe the force of spray through

the various nozzles of the jet head 14 or by regulating the needle valves 8 will adjust the pressure through the several nozzles so that the fuel will be spread evenly over the entire grate surface of the fire box. The 70 steam inlet to the steam chest can be readily controlled by operating the valve 13. The improvement is of an extremely simple construction, which may be easily installed, and cheaply manufactured. The parts constituting the improvement may be readily disassociated for replacements or repairs without requiring a great amount of physical exertion. The advantages of my improvement will, it is thought, be perfectly apparent and appreciated by those skilled in the art to which such invention relates. 75 80

With my improvement should the fireman on the locomotive or in the terminal leave the fire so that the same gets into the stoker 85 pot under the distributor and burn this portion of the device the end of the distributor could be easily taken off and a new end applied without renewing the whole distributor. Otherwise, this would be a very 90 expensive proposition. Thus by making my improvement of a two piece casting the trouble and expense usually occurring from this cause is greatly reduced. Also my particular construction eliminates the necessity 95 of making new valve bonnets and spuds and drilling out and tapping the steam chest so that new parts can be applied. Also the distributor can be applied well below the high velocity in the upper part of the fire box, 100 making it positively sure that an equal distribution of coal can be placed in the fire box at all times and under any and all conditions. Furthermore should it be found necessary to make any repairs to the distributor at any time, the distributor can be 105 taken out of the fire box without smouldering or otherwise interfering with the fire and repairs can then be made to the distributor while the same can be again readily 110 applied. This is not true with respect to any other class of distributors with which I am acquainted.

Having described the invention, I claim:—
In an apparatus of the class described, a 115 steam distributor head, having an outer rounded end, and substantially equidistantly spaced longitudinal passages extending therethrough, nozzles screwed in the head and communicating with the respective passages, said head having an inner thickened and widened end that is centrally formed with a lug, a steam chest comprising a block having a steam chamber therein and having one of its faces formed with a pocket to receive the lug of the distributor head therein, a compressible gasket between the confronting ends of the steam chest and head, removable means connecting the chest and head, nipples screwed through the steam 120 125 130

chest and communicating with the respective passages in the head, outer and larger nipples screwed through the outer end of a steam chest and arranged opposite the first mentioned nipples, needle valves screwed through the last mentioned nipples and finding seats in the first mentioned nipples, a

packing box on the last mentioned nipples for each of the needle valves and a valve controlled steam inlet pipe for the chamber ¹⁰ of the steam chest.

In testimony whereof I affix my signature.

GLENN O. WILLHIDE.
